(57) **CLAIM**

The ornamental design for a robot docking station, as shown
and described.

DESCRIPTION

FIG. 1 is a front view of a robot docking station showing the
claimed design;

FIG. 2 is a rear view thereof;

FIG. 3 is a top view thereof;

FIG. 4 is a bottom view thereof;

FIG. 5 is a left view thereof;

FIG. 6 is a right view thereof;

FIG. 7 is a perspective front, top, right view thereof;

FIG. 8 is a perspective front, top, left view thereof;

FIG. 9 is a perspective rear, top, right view thereof; and,

FIG. 10 is a perspective rear, top, left view thereof.

The broken lines shown in the drawings are for purposes of
illustrating portions of the robot docking station that form no
part of the claimed design.

1 Claim, 9 Drawing Sheets
